EINER HANSEN NORUNG, OF VALBY, NEAR COPENHAGEN, DENMARK.

CYLINDER LOCK.

Application filed February 12, 1924, Serial No. 692,389, and in Denmark February 12, 1923.

The present invention relates to a new lock of the kind in which two series of tumblers or locking members are employed. The peculiar feature of the new lock lies therein that the tumblers in the one series, after they have been set into a given position can be displaced as a whole a certain distance relatively to the other series, so that the first tumbler in the one series will come into engagement with a second tumbler in the other series and so on, and this displacement will, directly or indirectly seat in such a manner on the bolt of the lock, that the bolt is moved or released from a retaining mechanism so that it then can be moved by a separate handle.

10

The lock may be employed as spring-lock, door-lock, pad-lock, combination-lock and the like.

20

In the accompanying drawing a constructional form of the lock is shown. In this drawing—

Fig. 1 is a front view of a door-lock.

Fig. 2 is a longitudinal section of the lock 25 on the position at which the lock is locked.

Fig. 3 is a similar view of the lock in unlocked position.

Figs. 4 and 5 show the member which couples the lock with the bolt, in front and side 30 elevation, respectively.

Figs. 6, 7 and 8 show in front elevation and two sectional views which are taken at right angles to each other, a tumbler of the one series of tumblers.

35 Figs. 9 and 10 show in front view and section, respectively a tumbler of the other series of tumblers.

Figs. 11 and 12 show a raw blank for a key 40 in top and side view, respectively.

Fig. 13 shows the finished key produced by twisting the blank shown in Figs. 11 and 12.

The mechanism of the lock is enclosed in a cylindrical casing 41, which, on its front, has a projecting collar 42, which is visible on 45 the outside of the door. At its rear end the casing 41 is provided with screw threads on which a nut 43 may be screwed. A pin 44 prevents the casing from being turned relatively to the door into which it has been 50 fitted.

Within the casing 41 is fitted a cylindrical sleeve 45 to which is secured a pin 46, which 55 engages in a slot 47 in the casing 41, parallel to the axis. The sleeve 45 is somewhat shorter than the interior of the casing 41, and it can, therefore, be shifted to and fro

therein, but cannot be turned relatively thereto. The sleeve 45 has, on its inside recessed grooves 48 of which there is one less than there are inside tumblers 56, and into each of these grooves is placed a tumbler 49, Figs. 9 and 10. This tumbler consists of a piece of a ring, the shape of which corresponds to the shape of the groove 48. On the inner side of this piece of ring are two 60 teeth 50 which project into the interior space of the sleeve 45.

In the rear wall 51 of casing 41 is journalled a revoluble body 52, Figs. 4 and 5, the outer end of which is suitably connected with the bolt of the lock, not shown in the drawing, in such a manner, that the bolt is shot forward or withdrawn, respectively, when the said body 52 is turned. This body 52 has a cylindrical part 53, situated within the 70 casing 41 and within the sleeve 45. The part 53 has a radially disposed pin 54 which projects into an angle-shaped slot 55 in the sleeve 45. It is therefore only possible for the body 52 to be turned when the sleeve 45 75 is simultaneously displaced longitudinally.

Within the sleeve 45 are disposed a series of ring-shaped tumblers 56, Figs. 6-8. These are, along their circumference, provided with teeth and the spaces between the teeth correspond in shape to the teeth 50, Fig. 9. On each side of the tumblers 56 are two neighboring, continuous teeth gaps 57, whereas all other tooth-gaps are barred by means of a wall 58, Fig. 7. In the center of 90 the tumblers 56 is a cylindrical bore 59, which is, on the front face closed by a wall 60, in which there is a slot 61.

The width of the tumblers corresponds to the distance from center to center of grooves 95 48 on the inside of the sleeve 45. The tumblers 56 are arranged side by side between the cylindrical part 53 and a disc 64, Figs. 2 and 3. On the part 53 is provided a projection 65, and longitudinally extending 100 through the same and a part of part 53 is a slit 66, Fig. 4.

In the center of the face-plate 42 of the lock there is a circular key-hole 67, in the one side of which there is a notch 68, Fig. 1. Within the bore 67 there is a cylindrical recess 69, Figs. 2 and 3.

The key belonging to the lock is shown in Fig. 13. It is made of a flat piece of metal, has a wedge-shaped point 70 and a stud 71 arranged on the one side. Furthermore it has, as shown in Figs. 11 and 12, on both

sides a number of notches 72, the distance from center to center of which corresponds to the width of the tumblers 56. Lastly it is, as shown in Fig. 13, twisted in a special manner and this twisting is characteristic for each individual lock, or the relative angle-position of the tumbler-pairs in which it was locked.

When the key is inserted into the lock, the notches 72 will be situated between the slots 61 in the tumblers 56 and the key is twisted in such a manner that on the key being inserted into the lock, the tumblers will be turned through an angle which corresponds to a multiple of a tooth-gap in the tumblers 56.

The lock hereinbefore described acts in the following manner:

The key, Fig. 13, is inserted through the key-hole 67 and during this movement it will, by means of its wedge-shaped point 70 catch the tumblers 56 one after the other, by passing through the slots 61. When the key has been fully pushed into the lock its point 70 will be in the slot 66 in part 53 and, at the same time the stud 71 will have passed through notch 68 and will be within the recess 69. When, now, the key is turned, all tumblers 56 and the part 53 will be turned with it. A turning of part 53, however, is not possible, as said above, without the sleeve 45 being simultaneously displaced longitudinally, and by this displacement the tumblers 49 which are lying in the grooves 48 will be displaced from their engagement with one of the tumblers 56 to an engagement with the neighbouring tumbler 56. This is only possible if the teeth 50 exactly register with the tooth-gaps 57, Fig. 6, but this will always be the case, if it is the proper key, belonging to the lock, which is being employed. If it is a false key which has been inserted into the lock, at least one of the tumblers 56 will be in such a position that the teeth 50 do not register with the tooth-gaps 57 in the neighbouring tumbler 56, and the wall 58 will then prevent a longitudinal displacement of the sleeve 45, so that a turning of the part 52 and an unlocking of the lock is not possible.

The key can be removed from the lock in that position only at which stud 71 stands in front of notch 68 in the front wall of the lock casing. The lock described is, therefore, best suited as spring lock. If it be desirable that the key be removed when the bolt is withdrawn, there must be yet another notch of a similar kind as notch 68 provided in the key hole 67, which second notch must be situated opposite the stud 71 when the latter is in position with the bolt withdrawn and the pin 54 situated in the opposite side of the angle-shaped slot 55 in the sleeve 45.

By the key being drawn out from the lock,

the tumblers 56 will be turned thus that the slots 61 will all be brought to lie parallel with the slot 66. When the key is again inserted into the lock, the tumblers will, in consequence of the peculiar twist of the key, be turned into the position, at which the aforementioned longitudinal displacement of the sleeve 45 together with the tumblers 49 can take place relatively to the tumblers 56.

When the lock is to be altered in such a manner that it must be opened and fastened by a key different from the original one, then remove the pin 71 from the original key, insert the latter into the lock, and open this in such a manner, that the bolt is drawn back. Then pull the key out of the lock; the key now being deprived of its holding-pin 71.

Then insert the new key, of which the corresponding pin 71 has also been removed in order to enable the key to be inserted into the lock. Now the lock should be fastened by the new key, whereafter the latter should be pulled out, and the pin 71 screwed on to it. Henceforth the new key only will be able to open and fasten the lock.

The invention can also be employed in many other constructional forms than this shown in the accompanying drawing and hereinbefore described.

I claim:

1. In a lock, two series of tumblers, the tumblers in the one series having teeth, adapted to engage in the unlocking operation, corresponding means in the tumblers of the other series to thereby couple the individual tumblers of the first and second series, respectively, in pairs, the tumblers in the one of the series, when set to a given position, being displaceable, all together as a whole, relatively, to the other series by the movement of said tumblers, so that the first tumbler in the one series will come into engagement with a second tumbler in the other series and means for withdrawing the bolt of the lock by such displacement.

2. In a lock two series of tumblers, the tumblers in the one series having teeth, adapted to engage in the unlocking operation, corresponding means in the tumblers of the other series to thereby couple the individual tumblers of the first and second series, respectively, in pairs, the tumblers of both series having teeth, arranged to engage each one of the first series to each one of the second series individually and in several relative different positions of one to the other in the pairs, in the locking operation, and means for operating the bolt of the lock by such displacement.

3. In a lock two series of tumblers, the tumblers in the one series having teeth, arranged to engage in the unlocking operation, corresponding means in the tumblers of the

other series to thereby couple the individual tumblers of the first and second series, respectively, in pairs, a sleeve having slots in which the tumblers in the one series are disposed, said sleeve enclosing the tumblers of the other series, the tumblers of the other series being adjustable by a specially formed key and axially displaceable, all together as a whole relatively to the other series by the movement of said tumblers, and means for withdrawing the bolt of the lock by such displacement.

4. In a lock two series of tumblers, the tumblers of the one series having teeth, adapted to engage in the unlocking operation, corresponding means in the tumblers of the other series to thereby couple the individual tumblers of the first and second series, respectively, in pairs, a sleeve having slots in which the tumblers in the one series are disposed, said sleeve enclosing the tumblers of the other series, the tumblers of the other series being adjustable by a specially formed key, a casing in which the said sleeve is axially displaceably fitted, a revoluble pin, in the rear wall of said casing coupled to the bolt of the lock, said pin having means for engaging and displacing said displaceable sleeve and means for operating the bolt of the lock, by such displacement of said sleeve.

5. In a lock two series of tumblers, the tumblers of the one series having teeth, adapted to engage in the unlocking operation, corresponding means in the tumblers of the other series to thereby couple the individual tumblers of the first and second series, respectively, in pairs, a sleeve having slots in its inner side in which the tumblers in the one series are disposed, said sleeve enclosing the tumblers of the other series, the tumblers of the other series being adjustable by a specially formed key, a casing in which the said sleeve is axially displaceably fitted a revoluble pin, in the rear wall of said casing coupled to the bolt of the lock, said pin having a transverse stud and said sleeve having an oblique slot in which said stud is engaged, the tumblers enclosed by said sleeve having the shape of rings, and said rings being toothed on their outer face, a wall by which the tooth-gaps of said teeth are substantially closed, said tumblers hav-

ing a central slot, a key for connection therein, said key twisted and arranged to set the tumblers into which it is inserted into given positions, said key also having a point in which said point is engageable and said revoluble pin having a slot, and means to operate the bolt of the lock by the displacement of said sleeve.

6. In a lock two series of tumblers, the tumblers of the one series being adapted to engage the tumblers of the other series and thereby be coupled therewith in pairs, a sleeve having slots in which the tumblers in the one series are disposed, said sleeve enclosing the tumblers of the other series, a key to adjust the tumblers of the said other series, a casing in which the said sleeve is axially displaceably fitted a revoluble pin in the rear wall of said casing coupled to the bolt of the lock, said pin having a transverse stud, and said sleeve having an oblique slot in which said stud is engaged, the tumblers enclosed by said sleeve having the shape of rings, said rings being toothed on their outer face, a remaining wall by which the tooth gaps of said teeth are substantially closed, said tumblers having a central slot, a key for insertion in said slot to set the tumblers into which it is inserted, into given positions, said key also having a point, and said revoluble pin having a slot in which said point is engaged the tumblers in the outer series having a tooth corresponding in shape to the gaps between the teeth of the tumblers of the inner series and adapted to engage therein when the said inner series of tumblers is axially displaced, and to operate the bolt of the lock, by the displacement of said sleeve.

7. In a lock two series of tumblers, the tumblers in the one series having teeth, adapted to engage in the unlocking operation, corresponding means in the tumblers of the other series to thereby couple the individual tumblers of the first and second series respectively, in pairs, a key, having the shape of a bar, twisted to an irregular form, and having wings provided with notches, said notches lying between the tumblers, when the key is inserted in the lock.

In witness whereof he affixes his signature.

EINER HANSEN NORUNG.
